UNITED STATES PATENT OFFICE.

CARL R. WALLER, OF TRENTON, NEW JERSEY, ASSIGNOR TO DE LAVAL STEAM TURBINE COMPANY, OF TRENTON, NEW JERSEY, A CORPORATION OF NEW JERSEY.

GOVERNING MEANS FOR TURBINES.

Application filed May 19, 1922. Serial No. 562,215.

My invention relates to governing means for turbines. The object of my invention is to provide governing means adapted for the accurate control of a turbine automatically under any variation of load conditions and at the same time regulate the amount of steam supplied to or received from the low pressure system service line which receives steam from other sources and supplies steam to other sources, and maintain therein a constant pressure.

The governing means in accordance with my invention is adaptable for use in connection with such turbines as straight high pressure condensing, straight low pressure condensing, combination high and low pressure, or bleeder turbines in which steam is extracted from an intermediate stage.

By virtue of my invention, the turbine will be automatically controlled with accuracy under any variation in load conditions and will insure high efficiency and economy in the operation of the turbine.

Having now indicated in a general way the nature and purpose of my invention, I will proceed to a detailed description of a preferred embodiment thereof, as applied to a combination high and low pressure turbine, with reference to the accompanying drawings, in which—

Fig. 1 is a plan view of a turbine equipped with governing means embodying my invention.

Fig. 2 is an end view of the turbine shown in Fig. 1.

Fig. 3 is a longitudinal section on the turbine shaft.

Fig. 4 is a cross-section on line 4—4 Fig. 3.

Fig. 5 is a section on line 5—5 Fig. 1 showing valve connections.

In the drawings A designates the casing of the turbine, 5 the turbine shaft mounted in bearings 9 and extends into a gear casing A' having gearing therein through which the shaft to be driven is connected. Mounted on the shaft 5 are the runners 6, 6, and 7, 7, of the high and low pressure stages, respectively, of the turbine. 8, 8 designate packing means surrounding the shaft 5 where the shaft extends through the casing A.

1 designates a steam chest to which high pressure steam is delivered as hereinafter described. The steam chest 1 is in communica-

tion with chamber 1^a containing the first runner 6 of the high pressure stage by means of nozzles 1^b which deliver steam to the buckets of said runner. c' is a diaphragm between the chamber 1^a and a chamber 2 in the casing A, and is provided with nozzles for delivering steam to the buckets of the second runner 6, of the high pressure stage of the turbine from chamber 1^a.

d is a diaphragm between a chamber e and chambers 2 and 3 the latter two of which are separated from each other by partitions as shown in Fig. 4. Chamber 2 is connected to an exhaust pipe F hereinafter described, while chamber 3 is in communication with chamber e by means of nozzles 11 in diaphragm d, which deliver steam to the buckets of the first runner 7 of the low pressure stage of the turbine. The nozzles in the upper portion of diaphragm d are plugged so that no steam passes from chamber 2 to chamber e. f is a diaphragm between chamber e and a chamber f' communicating with an exhaust port 4, and which diaphragm is provided with nozzles for delivering steam to the second runner 7 of the low pressure stage of the turbine.

N is a high pressure steam pipe connected to the steam chest 1, and connected to this pipe is a throttle valve M and a high pressure steam control valve B.

Connected to the exhaust port or pipe F communicating with chamber 2 and a steam inlet pipe or port F' communicating with chamber 3, is a piping system K, which might be termed a low pressure steam receiver. Connected in the piping system K between ports F and F' are control valves C and H. Connected to the piping system K is a pipe K' leading to a low pressure steam service line, which may receive steam from various sources and from which steam may be delivered to various sources. G is a cut off valve between pipes K and K', whereby the low pressure service line may be cut off from the low pressure steam receiver of the turbine.

D is a governor which is driven from the turbine shaft 5 by means of a worm and worm wheel 10. The governor D is connected by means of lever mechanism b and c, to valve actuating mechanism of fluid actuated motors connected to valves B and C, respectively, for opening and closing said valves. L is a regulator of well known

type having a diaphragm within a chamber therein which is connected to lever mechanism *h* connected to valve actuating mechanism of a fluid actuated motor which is connected to the regulating valve *H*. The diaphragm chamber in regulator *L* is connected to the pipe *K* or the low pressure steam receiver by means of a pipe *l'*, whereby the regulator is controlled by the pressure in the low pressure steam receiver, so that the position of valve *H* is under the direct control of the pressure in said receiver.

Assuming that valve *G* is closed and valves *C* and *H* are held open for illustration, steam would pass from steam chest 1 through the high pressure stage of the turbine, then through the receiver *K* from chamber 2 to chamber 3, through the low pressure stage of the turbine and out through port 4 to a condenser, and valve *B* would be moved by the governor and the control mechanism to supply the required amount of steam to turbine for the load on the turbine.

In the normal operation of the system the valve *G* is open, low pressure steam is delivered from various sources to pipe *K'* and from which steam is drawn for various purposes, while high pressure steam is delivered to pipe *N*. Assuming now that valves *B*, *C* and *H* are in such positions as to feed high pressure steam through valve *B* to the high pressure stage of the turbine, feed steam from the low pressure receiver *K* to the low pressure stage of the turbine while steam is bled from said receiver by the low pressure steam service line through pipe *K'* and if the demand for steam from said low pressure service line does not vary or the load on the turbine vary the valves will remain in the above named set positions. If the demand for steam from low pressure service line is increased the pressure in said line will fall which will reduce the pressure in regulator *L*, which will in turn move valve *H* toward its closed position so that more steam will be bled from the receiver *K* between the two stages of the turbine by the said service line, and less steam will be delivered to the low pressure stage of the turbine. If the pressure increases in the low pressure service line the valve *H* will be moved towards its open position so that more steam will pass from the receiver to the low pressure stage of the turbine.

In both of above cases valve *B* will be actuated to control the flow of steam in accordance with the power demands on the turbine. The mechanisms for controlling valves *B* and *C* are so adjusted relative to each other that the valve *C* is always open when valve *B* is open and the valve *C* will not start to close until valve *B* is wholly closed. Thus in case of excessive pressure in

the low pressure service line and a light load on the turbine low pressure steam from the low pressure service line will pass through the low pressure stage of the turbine to exhaust 4 and operate the turbine even though valve *B* is held closed by the governor *D*.

The stem *B'* of valve *B* carries four disk valve members *B*², see Fig. 5, which have a relatively short movement from their full open positions to their closed positions, and as there is a simple lever connection between the governor *D* and motor valve mechanism *b* of valve *B* while the actuating mechanism *a* for the motor for valve *C* is of the compound type, it can readily be seen that slight variations in the governor *D* will affect valve *B* without affecting valve *C*.

It will now be obvious that by virtue of my invention a substantially constant pressure may be maintained in the external low pressure steam piping system and economically utilized in the turbine, and for factory use. It will be obvious that a series of turbines may be connected to the external low pressure piping system, and that the individual turbine will be automatically and accurately controlled.

Having now fully described my invention, what I claim and desire to protect by Letters Patent is:

1. Governing means for turbines having high and low pressure stages, comprising a high pressure steam control, a low pressure steam receiver adapted to receive steam exhausted from the high pressure stage of the turbine and deliver steam to the low pressure stage, low pressure steam control means, and other means actuated by the pressure in the low pressure receiver for controlling the passage of steam from said receiver to the low pressure stage, thereby tending to maintain the pressure in the receiver constant.

2. Governing means for turbines having high and low pressure stages, a governor, a low pressure steam receiver adapted to receive steam exhausted from the high pressure stage of the turbine and deliver steam to the low pressure stage, a governor controlled valve for controlling the passage of the steam to the low pressure stage, and a second valve controlled by the pressure in the receiver for also controlling the admission of steam from said receiver to the governor controlled valve for the low pressure stage.

3. Governing means for turbines having high and low pressure stages, a governor, a valve under control of the governor for admitting steam to the high pressure stage, a low pressure steam receiver adapted to receive steam exhausted from the high pressure stage of the turbine and deliver steam to the low pressure stage, a governor controlled valve for controlling the passage of steam to the low pressure stage, and a second

valve controlled by the pressure in the receiver for controlling the admission of steam from said receiver to the governor controlled valve for the low pressure stage.

5 4. Governing means for turbines having high and low pressure stages, a steam receiver between the high and low pressure stages connected to a low pressure steam service line, to which the exhaust from the 10 high pressure stage is adapted to pass, a valve for controlling the admission of steam to the high pressure stage, a governor for controlling said valve, a valve for controlling the admission of steam to the low pressure 15 stage controlled by said governor, a third valve for controlling the passage of steam from the receiver to the last mentioned valve, and a device actuated by the pressure in the receiver for actuating the third valve.

20 5. Governing means for turbines having

high and low pressure stages, a high pressure steam supply, a low pressure steam receiver connected to a low pressure steam service line and adapted to receive exhaust steam from the high pressure stage and for supplying steam to the low pressure stage, a governor, a valve actuated by the governor for controlling the admission of steam to the high pressure stage, a second valve connected to the governor for controlling the admission 25 of steam to the low pressure stage, a third valve for controlling the passage of steam from the low pressure steam receiver to the second valve, and means controlled by the pressure in the low pressure steam receiver 30 for opening and closing the third valve.

In testimony of which invention, I have hereunto set my hand, at Trenton, N. J., on this day of May 15th, 1922.

CARL R. WALLER.
